METHOD AND APPARATUS FOR ELECTRICAL DEHYDRATION

Paul W. Prutzman, Los Angeles, Calif., assignor
to Socony-Vacuum Corporation, New York,
N. Y., a corporation of New York

Application October 10, 1933, Serial No. 692,977

5 Claims. (Cl. 204—24)

The object of my invention is to provide means and a method for simultaneously resolving and separating the phases of an emulsion of the water-in-oil type, and more specifically a petroleum emulsion.

The method of resolving emulsions which consists in subjecting them to the action of a high tension electrical field was disclosed by Cottrell and others as early as 1911 (see U. S. Patent 987,115), is very well known and understood and needs but the briefest description.

In general terms, the emulsion is passed between opposite charged electrodes on which a high potential is impressed. This potential produces a static electrical field between the electrodes and, under the influence of this field, electrical charges are imparted to the suspended water particles. These charges cause the particles to approach each other and to coalesce to larger particles and droplets which finally attain such dimensions as to settle out of the oil.

This is purely a static effect and ceases if any material leakage or conduction between the electrodes occurs. The tendency of the liberated water particles is to arrange themselves along the lines of force at such minute intervals as to form conductive "chains" by breaking down the dielectric oil layer between them. When this occurs, the static field is dissipated by conduction and the resolving effect ceases until the field is reestablished.

In order to maintain the integrity of the field and the continued functioning of its resolving effect, it is necessary to maintain a dielectric barrier between the electrodes at all times. To this end several methods have been proposed. Cottrell (Patent 987,115) dilutes the emulsified oil with relatively dry oil, by which step the distance between the water particles and the thickness of the dielectric oil barrier between them is increased. Fisher (Patent 1,838,928) interposes a barrier layer of relatively dry oil between one of the electrodes and a layer or stream of emulsion which is in contact with the opposite electrode. Peek (Patent 1,170,184) interposes a solid dielectric barrier such as glass between one of the electrodes and a layer of emulsion which is in contact with the opposite electrode. McKibben (Patent 1,276,386) sweeps the water particles out of the field as fast as they are formed, thus maintaining in the field a constantly renewed supply of emulsion which, prior to resolution, has usually a high dielectric value.

The method of the instant application adopts the latter alternative and is directed to a specific

method and means for passing a constantly renewed supply of emulsion through a succession of high intensity fields into interposed zones of quiescence from which free water is drained to a point outside the apparatus.

The objects and advantages of the invention may best be understood with reference to the attached drawing, which represents in vertical section and internal elevation a preferred form of apparatus which may be used to illustrate the method employed.

Referring to the drawing, 10 is a substantially closed shell which may be of any preferred dimensions. This shell is divided into a plurality of compartments 11a, 11b, etc. by partition members which may consist, as shown at the right side of the drawing, of a ring 12 tightly attached to the shell, a truncated cone 13 attached to the ring, and a relatively short nozzle 14 attached to the upper end of the cone. Alternatively the opening through the plate may be of the same diameter as the nozzle, which may then be of greater length and attached directly to the ring without the use of the cone, as shown in dotted lines at 37.

The upper end of each nozzle is faced off square and opposed to this faced end is a cup shaped member 15, having its downwardly projecting rim aligned with the upper rim of the nozzle and spaced therefrom to leave a circumferential slot 30 21a, 21b, etc. These cups are firmly attached to a stiff rod or tube 16, which will be closed at the lower end as at 17 if a tube is used.

The rod or tube 16 passes through an insulator 18 fixed in the upper head of the shell and may 35 be threaded as at 19 and provided with a hand nut 20 for raising and lowering. If the rod is made movable in this manner, it should be passed through a stuffing box not shown.

A cable 22 connects an end of rod 16 with one 40 terminal of the secondary winding of a step-up transformer 23, the other secondary terminal being grounded as at 24. The primary winding has its terminals connected to a source of supply of alternating current. The shell itself should be 45 grounded, as indicated at 36.

When connected in this manner, the upper rim of nozzle 14 is the effective part of the grounded electrode, being conductively attached to the shell, while the cup 15 functions as the live electrode.

An emulsion supply pipe 25 communicates with the lower compartment 11a at an intermediate point in its height. An outlet pipe 26 is attached to the upper head of the shell, this pipe branching as at 27 to act as a vent for gas or 55

vapor which may be released within the apparatus and at 28 to conduct away treated oil. A water drain pipe 30 branches at 29-29 to each compartment, each of these branches being optionally controlled by a manual valve 31 or a float actuated valve 32 adapted to maintain a substantially constant water level 33 in the compartment, the latter being preferred. A sight glass indicated at 34 or a succession of try-cocks 35 may be used to indicate the momentary water level, these being particularly useful for manual control.

It is essential that the rims of cups 15 and nozzles 14 be maintained in substantial alignment and if the length of the insulator 18 and the bearing of the rod 16 therein do not suffice for this purpose, a lower insulator 38 supported as by a cross-bar 39 may be used. This insulator should be recessed as at 40 to permit vertical travel of the rod.

The above described apparatus is operated in the following manner. Emulsion or emulsified oil is introduced into the lower compartment 11a, in which any free water accompanying it is given an opportunity to settle out, to be withdrawn through pipe 29. The emulsion may be pre-heated to any desired temperature, but it is desirable to refrain from avoidably heating it after it enters the apparatus.

30 The settled emulsion moves slowly upward in the lower compartment and passes through the slot 21a into the next higher compartment 11b. A desired electrical potential, as of the order of 5,000 to 12,000 volts, being impressed on the electrodes, a highly concentrated field is established in the slot or gap 21a, the width of this gap and, by consequence, the intensity of the field, being variable by raising or lowering rod 16.

In passing through this field the emulsion is 40 partially resolved into its constituents in the well known manner, and such velocity is maintained through the gap as to sweep away the liberated water particles as fast as they are formed, thus preventing the formation of conductive water 45 chains and the dissipation of the field.

The resolution products, consisting of oil containing unbroken emulsion and suspended drops of free water, emerge from gap 21a into compartment 11b, where their velocity is so retarded 50 that the free water has ample opportunity to settle from the oil and join the water layer in the bottom of the compartment, from which it is withdrawn. The oil thus freed from water moves upwardly through the compartment, to and through the next field, and the above operations 55 are repeated as many times as there are fields, the rate of flow being so adjusted that after passing through the last field the emulsion will have been completely resolved, the final compartment 11d receiving only completely treated 60 oil and a residual quantity of suspended water. This water having been removed in the final compartment, only treated oil is delivered to outlet pipe 28.

65 As the flow of oil through the apparatus is solely in an upward direction, gas or vapor carried into or disengaged in any compartment is carried with the oil through all succeeding compartments and is finally discharged along with the treated oil through pipe 26.

Inasmuch as the oil is progressively deprived of emulsion in its passage from field to field, and the free water thus produced is removed from each stage, it is feasible and in most cases desirable to progressively decrease the width of the 75

field gaps 21 in the direction of oil flow. This provision is made in the original spacing of the live electrodes 15 on the electrode rod 16. In thus decreasing the width of the gap the field is correspondingly intensified so that the most stubborn residual traces of emulsion may be completely resolved.

The structure shown is adapted to the treatment of any emulsion in which water is the dispersed phase, no matter how refractory, and will 10 produce a complete resolution of the emulsion and final separation of the phases in a single pass through the treater.

The apparatus shown has important advantages over other dehydrating apparatus heretofore disclosed. As the electrodes are of relatively thin sheet metal (a thickness of one-eighth inch is ample), the field is highly concentrated at the opposed edges. As these edges are identical in circumferential length, each individual 20 field has the same intensity adjacent each edge. The relative intensities of the successive fields may be varied at will, and the intensities of all the fields may be simultaneously varied to suit different classes of emulsion. The provision of 25 retardation chambers and of means for removing water from each, together with the positive direction of the emulsion through the successive fields, permits the maintenance of fields of extremely high intensity and effectiveness.

30 I claim as my invention:

1. An electrical dehydrator comprising: a vertically arranged and substantially closed shell; a grounded electrode in the form of a horizontal partition conductively attached to said shell and 35 a nozzle projected upwardly around an opening through said partition, said nozzle and said partition dividing said shell into chambers and co-operating with the wall of said shell to form a receptacle for water; a live electrode in the form 40 of a cup having a vertical rim downwardly projected toward the upper end of said nozzle and aligned therewith; means insulated from said shell for supporting said cup with its lower edge in spaced relation to the upper edge of said 45 nozzle; means for introducing emulsion into the chamber below said electrodes and for forcing said emulsion between said electrodes into the chamber above said electrodes; means for withdrawing oil and gas from said upper chamber; 50 means for withdrawing water from the lower portion of said lower chamber; means independent of last said means for withdrawing water from the receptacle formed by said grounded electrode, and means for impressing an electrical potential 55 on said electrodes.

2. Apparatus substantially as and for the purpose set forth in claim 1, including means for controlling the space relation between said cup and said nozzle.

3. Apparatus substantially as and for the purpose set forth in claim 1, including a plurality of said partitions, nozzles and cups dividing said shell into chambers and forming a plurality of receptacles for water, the sole communication between adjacent of said receptacles being the annular space between said electrodes.

4. Apparatus substantially as and for the purpose set forth in claim 1, including a plurality of said partitions, nozzles and cups, said cups being 7 so arranged on said supporting means that the space relation between each cup and its corresponding nozzle is greater than the space relation between the cup and nozzle next thereto above.

5. Apparatus substantially as and for the purpose set forth in claim 1, including a plurality of said partitions, nozzles and cups, said cups being so arranged on said supporting means that the space relation between each cup and its corresponding nozzle is greater than the space rela-

tion between the cup and nozzle next thereabove, and including means for raising and lowering said cups to simultaneously and equally vary the space relation between each said cup and its corresponding nozzle. 5

PAUL W. PRUTZMAN.
